ATTORNEY

UNITED STATES PATENT OFFICE.

OLYMPIO F. GAMBATTI, OF HOUSTON, TEXAS.

COMBINED FILTERING AND HEATING DEVICE.

984,552.

Specification of Letters Patent. Patented Feb. 21, 1911.

Application filed June 25, 1909. Serial No. 504,250.

To all whom it may concern:

Be it known that I, OLYMPIO F. GAMBATTI, a citizen of the United States, residing at Houston, in the county of Harris and State 5 of Texas, have invented certain new and useful Improvements in Combined Filtering and Heating Devices, of which the following is a specification.

My invention relates to new and useful 10 improvements in combined filtering and heating devices.

The accompanying drawing illustrates the device as attached to a dental chair.

The object of the invention is to provide a 15 device of the character described, whereby either hot or cold filtered water may be instantly supplied to the patient, or for any other purpose.

Another object of the invention resides in 20 the provision of means whereby the device may be readily attached to a chair or other support.

Finally, the object of the invention is to 25 produce a device of the character described that will be compact and practical, one that will be easily attached to the chair, and one that will be inexpensively produced and easily kept in repair.

With the above and other objects in view, 30 my invention has particular relation to certain novel features of construction and operation, an example of which is given in this specification and illustrated in the accompanying drawings, wherein the figure is a 35 side elevation of the attachment secured to the arm of a chair and having a portion of the heater as well as a portion of the filter broken away to show the operative mechanism within.

Referring now more particularly to the 40 drawings, the numeral 1 refers to the arm of the chair to which the attachment is secured, and 2 designates a filter which is attached to said arm by means of a tubular 45 hinge member 3. Water is introduced into this filter through the main supply pipe, 5, which has a union with the hinge member, 3, through which the water passes into the filter, and is forced through filtering stone 6, 50 by the water pressure, and thereby filtered. My improved heating attachment is also connected with the filter by means of a connecting elbow, 10. This attachment includes a double pipe arrangement, the pipes 55 11 and 12 of which unite at one end and

connect with elbow 10 and also unite at their other end in the outlet pipe 13. The unions connecting the heating attachment to its connecting pipes are of such a nature that said attachment may be readily removed 60 and replaced.

Pipe 12 carries an electric heater, 14, of any desirable type which is provided with the usual connecting wires, 15. These wires have a suitable connection with a generator 65 (not shown). This heater attachment is provided with suitable valves, 16 and 17, operable in any desired manner, as by the ordinary thumb buttons. By means of this arrangement, when hot water is wanted the 70 valve 16 may be opened and the water will be discharged from the filter through pipe 12, which carries the heater, and pass through pipe 13 into receptacle 18, carried by receptacle holder 19; and when cold 75 water is desired, valve 17 may be opened and the water will pass through pipes 11 and 13 into said receptacle.

While I have shown this specific form of the attachment, which is my preferred form, 80 I do not wish to limit myself to the exact form shown, but desire to secure protection upon such modifications thereof as may fall within the scope of the invention.

An attachment, constructed in accordance 85 with the foregoing description and the drawing accompanying the same, will be found to be compact, practical, and very convenient for the purposes for which it is 90 designed.

What I claim is:—

1. In a device of the character described the combination with an arm support of a combined filtering and heating device including a hinge supporting member, a filter carried thereby, a supply pipe for supplying the filter through the hinge member, a plurality of liquid conductors uniting in common supply and discharge pipes for relieving said filter and a heating device carried 95 by one of said conductors.

2. In a device of the character described the combination with an arm support of a combined filtering and heating device including a hinge supporting member, a filter carried thereby, a supply pipe for supplying the filter through the hinge member, a plurality of liquid conductors uniting in common supply and discharge pipes for relieving said filter, means of controlling the flow 105 110

of liquid through said conductors and a heating device carried by one of said conductors.

3. In a device of the character described
5 a combined filtering and heating device in-
cluding a supporting member and a filter
carried thereby, a supply pipe discharging
into said filter through said supporting
member, a relief pipe for said filter, a plu-
10 rality of liquid conductors which receive the
liquid from said relief pipe and conduct the
same to a common discharge, and a heating
apparatus carried by one of said conductors.
4. In a device of the character described
15 a combined filtering and heating device in-
cluding a supporting member and a filter

carried thereby, a supply pipe discharging
into said filter through said supporting
member, a relief pipe for said filter, a plu-
10 rality of liquid conductors which receive the
liquid from said relief pipe and conduct the
same to a common discharge, a heating ap-
paratus carried by one of said conductors
and means for controlling the flow of liquid
through said conductors. 25

In testimony whereof I have hereto set
my hand this the 21st day of June, A. D.
1909.

OLYMPIO F. GAMBATI.

In the presence of—

Wm. A. CATHEY,
E. C. GUY.
